UNITED STATES PATENT OFFICE.

FREDERICK A. HOSKINS, OF DUBUQUE, IOWA.

MINE-VENTILATING SYSTEM.

1,171,340.

Specification of Letters Patent.

Patented Feb. 8, 1916.

Application filed June 25, 1913. Serial No. 775,760.

To all whom it may concern:

Be it known that I, FREDERICK A. HOSKINS, a citizen of the United States, residing at Dubuque, in the county of Dubuque and State of Iowa, have invented certain new and useful Improvements in Mine-Ventilating Systems; and I do hereby declare the following to be a full, clear, and exact description of the invention, such as will 10 enable others skilled in the art to which it appertains to make and use the same.

This invention relates to improvements in ventilating systems for mines and has for its primary object the provision of means 15 whereby foul air and gases may be withdrawn from all parts of the mine and fresh air admitted to the mine.

Another object of the invention is to provide a novel ventilating system which may 20 be cheaply installed, easily operated, and very efficient.

With these and other objects in view, as will become more apparent as the description proceeds, the invention consists in certain novel features of construction, combination, and arrangement of parts, as will be 25 hereinafter described and claimed.

For a complete understanding of my invention, reference is to be had to the following 30 description and accompanying drawing, in which the figure illustrates a section through a mine illustrating my improved ventilating system.

Referring in detail to the drawing by numbers, 5 designates a mine chamber or drift which is communicant with the shaft 6.

In carrying out my invention I form a plurality of drill holes 7 which extend from the surface of the ground 9 downwardly to the drift or chamber 5. Any suitable number 40 of these drill holes may be provided, depending upon the length of the drift. Each drill hole is lined with a casing 10 which extends some distance above the surface of the ground. An air pipe 11 extends down the shaft 6 and connects with the horizontal air pipe 12 which extends through the drift adjacent the bottom and near the side thereof, as shown in the drawings. A plurality 45 of vertical pipes 13 extend upwardly from

the air pipe 12 and connect with the horizontal pipes 14 which extend to the position directly under the drill hole openings which are connected to the short vertical pipes 15 which extend a slight distance 55 within said openings. A valve 16 is carried by each of the pipes 13 and controls the flow of air therethrough. A plurality of short branch pipes 17 are connected to the pipe 12 and extend toward the center of 60 the drift and are for the purpose of admitting air into the same. A flow of air through these pipes is controlled by the valve 18.

When the ventilating system is in operation, compressed air is forced down the pipe 11 and through the pipe 12 and may be discharged directly into the drill holes by means of the pipes 13, 14 and 15. The discharge of air into the casings 10 causes 70 an up draft which draws the foul air and gases from the mine chamber. The fresh air which discharges into the drift through the pipes 17 takes the place of the foul air and gases which have been discharged 75 through the drill holes.

To provide a convenient means of settling the dust within the mine so as to prevent an explosion, I provide a main water pipe 19 which extends through the drift and 80 which is provided with the branches or extensions 20 carrying the valves 21. A hose may be attached to the threaded extremities of the extensions 20 and used in wetting down the walls and ceiling of the drift. 85

From the foregoing description taken in connection with the accompanying drawings, it will be seen that my improved ventilating system will operate to maintain a safe healthful atmosphere within the mine 90 by withdrawing therefrom the foul air and gases and supplying the place with fresh air.

It is to be understood that while I have shown and described the preferred embodiment of my invention, I do not wish to be 95 limited to this exact construction, combination, and arrangement of parts, but may make such changes as will fall within the spirit and scope of the invention as defined by the appended claim.

Having thus described my invention, what I claim is:—

A mine ventilator including the combination with a mine drift and drill holes extending from the drift to the surface of the ground, of air exhausting means positioned in the drill holes and blow-out pipes, each located near the floor inclined upwardly

toward one wall of the drift and spaced from the wall toward which it is directed.

In testimony whereof I affix my signature in presence of two witnesses.

FREDERICK A. HOSKINS.

Witnesses:

F. W. COATES,
JOSEPH T. LAGEN.
